DESIGN FOR A BOX OR SIMILAR CONTAINER

Harvey Avedon, East Elmhurst, N. Y.

Application October 2, 1935, Serial No. 58,799

Term of patent 7 years

To all whom it may concern:

Be it known that I, Harvey Avedon, a citizen of the United States, residing at East Elmhurst, county of Queens, and State of New York, have invented a new, original, and ornamental Design for a Box or Similar Container, of which the following is a specification, reference being had to the accompanying drawing, forming a part thereof.

In the drawing:

Fig. 1 is a side elevational view of the box or similar container, showing my new design.

Fig. 2 is a top view thereof.

I claim:—

The ornamental design for a box or similar container, substantially as shown.

HARVEY AVEDON.
